(57) **CLAIM**

I claim the ornamental design for a table lamp, as shown and described.

DESCRIPTION

FIG. 1 is a side upper perspective view of a table lamp of Applicant's design;

FIG. 2 is a front elevational view thereof;

FIG. 3 is a rear elevational view thereof;

FIG. 4 is a first side elevational view thereof, the side elevational view opposite the first side elevational view being a mirror image thereof;

FIG. 5 is a top plan view thereof; and,

FIG. 6 is a bottom plan view thereof.

The broken line disclosure represents portions of the lamp which form no part of the claimed design.
